(57) **CLAIM**

The ornamental design for a spiral magnetic vortex instrument, as shown and described.

DESCRIPTION

FIG. 1 is a top, front right perspective view of a spiral magnetic vortex instrument showing my new design;
FIG. 2 is a top, front left perspective view thereof;
FIG. 3 is a top, rear right perspective view thereof;
FIG. 4 is a top, rear left perspective view thereof;
FIG. 5 is a right side view thereof;
FIG. 6 is a left side view thereof;
FIG. 7 is a front view thereof;
FIG. 8 is a rear view thereof;
FIG. 9 is a bottom view thereof;
FIG. 10 is a top view thereof;
FIG. 11 is a front perspective view thereof; and,
FIG. 12 is a second front perspective view thereof.
